UNITED STATES PATENT OFFICE.

ALEXANDER WINTON, OF CLEVELAND, OHIO.

DESIGN FOR A FRAME FOR A MARINE EXPLOSION-ENGINE AND CONNECTED TRANSMISSION-CASING.

46,388.

Specification for Design.

Patented Sept. 8, 1914.

Application filed June 20, 1914. Serial No. 846,398. Term of patent 14 years.

To all whom it may concern:

Be it known that I, ALEXANDER WINTON, a citizen of the United States, residing at Cleveland, in the county of Cuyahoga and State of Ohio, have invented a new, original, and ornamental Design for a Frame for a Marine Explosion-Engine and Connected Transmission-Casing, of which the following is a specification, reference being had therein to the accompanying drawing.

This invention relates to improvements in designs for a frame for a marine explosion engine and connected transmission casing.

The improved design is shown in the accompanying perspective view.

I claim:

The ornamental design for a frame for a marine explosion engine and connected transmission casing, as shown.

In testimony whereof I hereunto affix my signature in the presence of two witnesses.

ALEXANDER WINTON.

Witnesses:

E. H. CROSS,
J. L. TRAUB.
